UNITED STATES PATENT OFFICE

CLIFFORD A. SCHACHT, OF HUNTINGTON, INDIANA

SLIDING CASTER

Application filed October 28, 1931. Serial No. 571,633.

This invention is a novel improvement in sliding casters or glides for furniture. The principal object of the invention is to produce a very simple easily applied caster or glide composed of a preferably circular shell having upturned outer edges and a central upwardly projecting portion of less height than the peripheral portions of the shell; and an attaching member, preferably a screw, adapted to fasten the shell to the leg of the table or chair and having a head on its lower end fitted in the recess, formed by the said projecting portion of the shell, and an annular groove just above the head engaged 10 with the upper end of the said inwardly projecting portion so as to practically permanently but rotatably connect the shell to the attaching member.

Another object is to provide the upper end 20 of the central upwardly projecting portion of the shell with integral spring tongues which will readily engage the annular groove in the attaching member when the latter is inserted in the shell and secure said member 25 to the shell.

A further object is to provide an elastic cushioning member in the shell, whereby the weight of the furniture may be yieldably supported on the shell.

Another object is to provide such a caster 30 with an elastic cushioning member parts of which project through the shell into contact with the surface on which the slider rests, so as to render the caster noiseless.

In the accompanying drawings I have illustrated several practical constructions of sliders embodying the invention but varying in specific features; and will explain the invention with reference to said drawings to enable others to adopt and use the same. In the claims the various novel features and combinations for which protection is desired 40 are concisely stated.

In the drawings:

Fig. 1 is a sectional view of a simple form of slider embodying the invention attached to the leg of an article of furniture.

Fig. 2 is a sectional view showing a variant of the slider shown in Fig. 1.

Fig. 3 is a plan view of the slider shown

in Fig. 2 showing the attaching member in section at the point of its connection with the shell.

Fig. 4 is a sectional view of a slider with a small elastic cushion fastened on the attaching member. 55

Fig. 5 is a view showing an elastic cushion seated in the shell.

Fig. 6 shows a variant of the elastic cushion. 60

Fig. 7 is a detail section on the line 7—7, Fig. 3.

Fig. 8 is a sectional view of another variant of the elastic cushion.

Fig. 9 is a plan view of the slider shown 65 in Fig. 8 detached.

Fig. 10 is a sectional view showing a construction wherein the rubber cushion projects through an opening in the bottom of the shell and renders the same noiseless. 70

Fig. 11 is a bottom plan view of the slider shown in Fig. 10.

Fig. 12 is a view similar to Fig. 10 showing a variant of the construction.

Fig. 13 is a plan view of the slider shown 75 in Fig. 12.

The shell or base 1 of the slider is preferably stamped out of sheet metal, in the form of an approximately circular disk having a peripheral external concavo convex flange 2, 80 and an upwardly extending cone-like projection 3 at its center of less height than the flange 2. This projection forms an approximately conical recess on the underside of the shell, and an approximately conical projection inside the shell. 85

Preferably the apex of the projection 3 is radially slotted as at 3^a, the portions between the slits forming tongues 3^b which are adapted to engage an annular groove 5^b in the attaching member 5 when the latter is properly engaged with the shell, as shown. 90

The attaching member 5 may be a screw or nail or pin or bolt adapted to be entered into the lower end of the leg L of a table or other piece of furniture. Preferably I employ a screw that can be readily fastened to the leg. As shown the attaching member 5 has a head 5^a and threaded shank and an annular groove 5^b in the shank close of the head. 100

In assembling the parts the attaching member 5 is forced upwardly through the slotted end of the conical projection 3 in the shell until the head 5^a thereof is seated in the conical recess in the bottom of the shell. The tongues 3^b yield sufficiently to permit the passage of the shank of the attaching member but when the latter is properly entered the tongues 3^b spring into and engage the groove 5^b, and will prevent the withdrawal of the attaching member. In this way the attaching member is securely but rotatably engaged with the shell.

In Fig. 1 the flange 2 is shown as provided 15 on its upper edge with serrations or teeth 2^a, which will bite into the wood of the leg L and prevent the slider rotating when the screw 5 is screwed tightly into the leg. In Figs. 2 to 8 the upper edge of the flange 2 is inturned 20 as at 2^b, so that the flange is concavo-convex in cross section. In Fig. 4 a cushion 4 of rubber or other resilient material is pressed 25 on the shank of the pintle 5 which when the slider is attached to the leg, forms a cushion between the lower end of the leg and the shell 1. In Fig. 5 an annular cushion 4^a of larger diameter is placed in the shell around the cone and will form a resilient cushion between the shell and the leg. In Fig. 6 an 30 annular cushion 4^b of suitable material is fitted within the flange 2 and around the protuberance 3 and will form a cushion between the shell and the leg when the slider is applied thereto. In Figs. 8 and 9 an annular cushioning member 4^c provided with 35 a conical opening 4^d larger at bottom than at top is fitted within the shell and nearly fills the same.

In the construction shown in Figs. 10 and 40 11 the shell is provided with openings 1^e in its bottom and the rubber cushion 4^d fills the shell and projects above the edge thereof and partly projects through the openings 1^e the projecting portions 4^e contacting with the 45 surface upon which the slider rests. In Figs. 12 and 13 the shell is provided with a series of circular openings 1^f in its bottom through which the cushion 4^b partially projects as indicated at 4^f. The construction shown in 50 Figs. 10 to 13 are particularly useful in schools where a noiseless slider is desired. In these constructions the projections extend below the shell, and the latter keeps the rubber from spreading. If an all rubber tip was 55 used it would go to pieces, whereas, the metal shell protects the rubber and if the projections wear down to the shell the slider could still be used on the chairs.

If no rubber inserts or cushions are employed, as in Fig. 1 then when the slider is attached to the chair the shell should be screwed up tightly against the leg.

The rubber cushions are made somewhat 60 higher than the shell so that after the slider is fastened to the chair the cushion will

project somewhat above the shell. In other words, the cushion is made somewhat higher and there is only a certain portion of same which will take up the contraction, therefore, there will be rubber between the chair and shell when it is applied so that the leg L does not rest upon the edge of the shell but is supported by the cushioning member. By having the large hole in the rubber cushion so that when the slider is fastened to the chair by means of the screw, the rubber will tend to press inwardly towards the screw and not over the metal shell.

The slider can be readily fastened to the leg of a chair by simply screwing the threaded shank of the attaching member into the lower end of the leg until the top of the flange 2, or cushion therein, of the shell 75 engages the lower end of the leg.

The loose connection between the attaching member and the shell permits a slight 80 tilting or rocking movement of the attaching member in the shell and also a slight axial movement, as well as rotation of the 85 attaching member in the shell, and when the rubber members as shown in Figs. 4, 5, 6, 8, 10 and 12 are used the members form 90 resilient cushions between the leg and shell. The loose connection afforded by the tongues 95 engaging the groove prevents the dropping of the attaching member out of the shell, and should the attaching member loosen in the leg it could not drop through the shell and 100 its head could not contact with the surface on which the slider rests. In the constructions in which the cushioning member fits 105 tightly around the attaching member it will also prevent dropping of the attaching member in the shell.

I claim:

1. A slider comprising a shell having a central recess on its underside and spring 110 tongues at the upper end of the recess, and an attaching member extending through the recess and having a head seated in the recess and a groove engaged by said tongues.

2. A slider comprising a shell provided 115 with a plurality of openings in its bottom, an attaching member connected with the shell, and a resilient cushioning member in the shell partly projecting through the said openings.

3. A slider comprising a shell having 120 openings in its bottom, a central recess on its underside and spring tongues at the upper end of the recess, an attaching member extending through the recess and having a head seated in the recess and a groove engaged by said tongues, and an annular cushioning member in the shell projecting 125 through the openings.

4. A slider comprising a shell having a central conical projection forming a recess 130

on its underside and spring tongues at the upper end of said projection, an attaching member extending through the recess and having a head seated in the recess and an 5 annular groove engaged by said tongues.

5. A slider of the character specified comprising a shell having openings in its bottom and a central conical projection forming a recess on its underside and spring 10 tongues at the upper end of said projection, an attaching member extending through the recess and having a head seated in the recess and an annular groove engaged by said tongues; and an annular cushioning 15 member in the shell projecting above the shell and through the openings.
